DEVICE PRODUCING ORNAMENTAL BUBBLE
EFFECTS AND METHODAbraham Abramson, New York, N. Y., assignor to
Raylite Electric Corp., Bronx, N. Y., a corpora-
tion of New York

Application February 21, 1946, Serial No. 649,157

11 Claims. (Cl. 240—10)

1

This invention relates to the manufacture of bubble-ornament devices, and more particularly is directed to the constructions of such device and a method of operating same.

Among the objects of the invention is to generally improve devices of the character described and the method of operation thereof which shall comprise few and easily assembled parts, which shall be economical to manufacture and adapted for quantity production so as to provide a cheap and inexpensive product, which shall be dependable and reliable in operation requiring a minimum of external heat supply, and which shall be practical and efficient to a high degree in use.

This invention is a continuation in part to the subject matter covered in applicant's like copending applications filed herewith and applications S. N. 598,569 (Patent No. 2,412,379) and 598,570, filed June 9, 1945, for Decorative illuminated devices and method.

Other objects accordingly consist of features of constructions and method, combinations of elements, arrangement of parts and steps in operation which will be exemplified in the constructions and method hereinafter described and of which the scope of the application will indicate in the following claims.

In the accompanying drawing in which possible illustrative embodiments of the invention are shown:

Fig. 1 is a front elevational view, partly broken away to expose the interior, showing a bubble-ornament device constructed to embody the invention.

Fig. 2 is an enlarged fragmentary front elevational view of the device shown in Fig. 1.

Fig. 3 is a cross sectional view taken on line 3—3 in Fig. 2.

Fig. 4 is a fragmentary front elevational view showing a modified form of the invention constructed with a different diaphragm.

Fig. 5 is a cross sectional view taken on line 5—5 in Fig. 4.

Fig. 6 is a fragmentary front elevational view like Fig. 4 showing another modified construction embodying the invention, and

Fig. 7 is a cross sectional view taken on line 7—7 in Fig. 6.

Heretofore ornamental bubbling devices of the character described used for various purposes required a high degree of skill in manufacture and assembly to obtain reliable predetermined desired result and reproductions. In the present invention such devices are made simple in construction and in method of operation, yet operate with pos-

itive assurance to give predetermined desired results with the unfailing reliability and dependability of performance.

To this end, as seen in the drawing there is provided an improved bubble-ornament device 10 constructed to embody the invention which is seen to include a vertically disposed transparent tube body made of glass or other translucent material designated as 11 having an integral closed lower or bottom end 11a, preferably made flat, and a sealed top end 11b. Said body portion 11, when the device 10 is intended to simulate a Christmas tree decoration may be made in appearance, such as outline, form, shape and size to simulate a candle.

In the form of the invention shown in Figs. 1 and 2, the tube body 11 contains a suitable readily volatilizable liquid 12, such as ether, wood alcohol or any others, well known in this art which is translucent, has a low boiling point and preferably is non-flammable such as mixture of methanol and carbon tetrachloride or methylene chloride. The liquid 12 may be placed into the tube body 11 through the upper or top end 11b thereof before fusing the latter for hermetically sealing said liquid 12 therein at a level so as to leave an adequate chamber or space 13 in said tube end 11b. Said sealed space 13 above the liquid 12 may be evacuated to permit lowering the boiling point normally required for the liquid 12. Said space 13 constitutes a condensing and heat dissipating means for liquefaction of bubbles 15 rising in the liquid 12 to the level thereof, as shown in Fig. 2.

There is also provided a diaphragm 16 of relatively thin sheet material fitted or seated in the lower end of tube body 11 preferably just short of the said bottom end 11a so as to leave a shallow chamber or section space 17 between said diaphragm 16 and bottom end 11a, for retaining activating vapors 18 generated as a vapor pocket from said liquid 12 in the manner hereinafter described.

When ether is used as the liquid 12, copper or brass is a desirable sheet material to use for the diaphragm 16 as it forms a protective means to eliminate possible explosive derivatives.

For supplying heat to operate device 10 any suitable source may be provided. As for example, as shown in Fig. 1, tube 11 is supported with the lower or bottom end 11a thereof located in close proximity to lamp bulb 20a of an incandescent lamp 20. The latter, as here shown, is mounted in an electric socket 21 of a Christmas tree lighting outfit (not shown) of any well un-

derstood construction by means of a sleeve holder or connector 22 made of fiber, glass, plastic or other non-combustible material. The lower end 22a of sleeve holder 22 may snugly fit over the lamp bulb 20a and the upper end 22b fit snugly over the lower or bottom tube end 11a so that the holder 22 provides a relatively firm interconnecting support or rigid coupling. The holder 22 also serves as a conduit to guide the surrounding air heat conducting medium from glowing lamp filament 20b of the lamp bulb 20a to the vapors 18 confined in shallow space 17 within the tube bottom end 11a, thus serving as a direct heating means for said vapor pocket.

In the device 10 shown in Figs. 1 and 2, the diaphragm 16 is preferably tightly wedged in the position shown about the periphery thereof and may be provided with an angular edge rim or flange 16b to increase the gripping effect and to retain the diaphragm 16 in set position against accident displacement. Said diaphragm 16 may be perforated with a central opening 16a which when said device 10 is operating, communicate the end of liquid column 12 at the diaphragm 16 with the vapor pocket 18 in space 17 of limited capacity therebelow to permit the formation of bubbles 15 in passing of a portion of said vapor pocket through said diaphragm opening 16a as hereinafter described.

In practising the invention, assuming the socket 21 is positioned on a Christmas tree (not shown) or arranged for other decorative display purposes and connected in an electric circuit power supply (not shown) for lighting the lamp 20 in the well understood manner, heat and light radiated from the lamp filament 20b is effective to vaporize any liquid 12 in the tube bottom space 17 and to form said vapor pocket and maintain said space 17 substantially filled with vapor 18.

The heat from lamp filament 20b beside producing said vaporization also provides heat to cause intermittent "flash" expulsion of a portion of the confined vapors 18 forming said pocket to expand through said diaphragm opening 16a into the liquid 12 thereabove in the form of a stream of flowing bubbles 15 rising through the liquid column 12. The sleeve holder 22 serves as a conduit to confine the heat conducting medium, namely, air, therein. Thus there is provided the degree of heat necessary from a minimum heat source at lamp filament 20b, sufficient light beams from the latter being projected through said diaphragm opening 16a to illuminate the liquid column 12 and bubbles 15 to produce an attractive activated bubble lighting effect.

The lighting of bulb 20 also illuminates the side walls of the transparent tube body 11 to the top end 11b thereof and imparts an appearance suggestive of a lighted candle.

It has been found an absolutely tight joint between the diaphragm flange 16b and the side walls of the tube body 11 is not required and that a slight leakage thereat does not affect the operation of the device 10, but provides a drain or seepage of the liquid column 12 into the vapor pocket 18 to replenish the same for the portion thereof forming bubbles 15.

The improved method embodying the invention in the form above described will now be apparent. The column of volatile liquid 12 within the tube body 11, which, when said device 10 is operating, extends between the diaphragm 16 and the top tube space 13, and is under less than atmospheric pressure because of the evacuated condition of said top space 13. Said liquid 12 has ex-

ternal illuminating radiant heat applied thereto, as by means of the glowing lamp filament 20b, which is directed to maintain bottom space 17 substantially filled with vapor and said vapor pocket 18 bubble-free. Heat from said lamp filament 20b is then being supplied to the vapor pocket 18 in said space 17, that is, in an effective degree sufficient to generate pressure periodically in excess of that due to the column of liquid 12 whereby "flash" expulsion of a portion of the vapor pocket 18 takes place intermittently expanding said vapor portion through diaphragm opening 16a bubbles 15 which float up in a stream through the liquid column 12. After each of said "flash" expulsions the pressure of vapors 18 in said pocket for an instance apparently is reduced and permits a small amount of liquid 12 to trickle into the bottom space 17 where it is vaporized for replenishing said bubbleless vapor pocket 18. The vapor pressure in said space 17 is thus successively built up in repeated succession and said "flash" expulsions passing through diaphragm opening 16a and expanding form bubbles 15 of relative uniform size streaming up through the liquid column 12. The flowing bubbles 15 rising through liquid column 12 produced are directly illuminated by light beams emanating from the lamp filament 20b in passing through said diaphragm opening 16a as seen from Figs. 1 and 2.

The bubbles 15 of the flowing stream on reaching top space 13 after passing through the liquid column 12 are cooled, condense and liquify for returning to the liquid 12 in tube body 11 and thereby replenishing same to continue the cycle of operation above described as long as said illuminating radiant heat from lamp filament 20b is directed to act on said vapors 18 of said pocket in bottom space 17. To be more accurate, said bubble-forming action continues to take place as long as there exists a heat gradient or differential temperature between the hotter portion of the vapor pocket 18 in space 17 forming bubbles 15 and the cooler liquid after liquefaction of bubbles in evacuated top space 13.

In Fig. 4, there is shown a modified form of the invention having a diaphragm 26 which differs from diaphragm 16, above described, by providing in place of central opening 16a, one or more peripheral through-passages or grooves 26a between rim edge or flange 26b and the side walls of tube body 11 as shown in Fig. 3. The method of operation for this modified form is the same as has been described with the construction assembly using diaphragm 16 and shown in Figs. 1, 2 and 2a. In each construction, like "flash" expulsions of said vapor pockets 18 and 28 are expanded to form bubbles 15. However, in the modified construction the bubbles 15 formation takes place through one of said passages 26a.

In Fig. 6 still another modified form of the invention is shown. Here an additional feature is added in providing granular porous particles 39, such as pumice, which practically fill bottom space 37 except for the vapor pocket 38 to increase the heat conductivity whereby starting of operation is facilitated. Diaphragm 36 may have a plurality of space through openings 36a therein and is positioned to keep the effective volume for vapor pocket 38 in the space 37 relatively small. The diaphragm openings 36a are preferably made small enough to retain said particles 39 within said space 37 as shown in Figs. 6 and 7. Likewise, pumice particles may also be provided in the spaces 17 and 27 of the modifications shown in Figs. 2 and 4, respectively.

The form of the invention shown in Figs. 3 and 4 operates in the same manner as has been described for device 10 and shown in Fig. 1, "flash" expulsions of vapor 28 and 38 of said pocket in space 27 and 37 forming bubbles 15 when expanding through one or more of said diaphragm passage openings 26a and 36a, respectively.

It is to be understood that each of the modified constructions described above may be assembled in holders 22 and supportingly mounted over incandescent lamp 20 in the manner described for device 10 and shown in Fig. 1.

It is therefore seen that there is provided improved devices and a method of operation in which the objects of the invention are achieved and which are well adapted to meet all conditions of practical use.

As various possible embodiments may be made in the above invention for use for different purposes and as various changes might be made in the embodiments and method above set forth, it is understood that all the above matters here set forth or shown in the accompanying drawing are to be interpreted as illustrative and not in a limiting sense.

Thus having described my invention, I claim as new and desire to secure by Letters Patent:

1. In a device of the character described producing ornamental bubble effects, a vertically disposed sealed transparent tube body, a translucent low-temperature boiling liquid column filling a mid-portion of said tube body, a thin sheet material diaphragm immovably positioned in the lower end of said tube body just short of the bottom thereof to provide a limited space thereat, heated vapors of said liquid column occupying said space at a pressure to retain the liquid column above the diaphragm, and means carried by the diaphragm communicating said vapors with the liquid column to permit "flash" expulsion of expanding portions of said vapors as bubbles into the liquid column and to permit seepage from the liquid column into said space.

2. A device as defined in claim 1 in which said communicating means includes a centrally located opening in the diaphragm.

3. A device as defined in claim 1 in which said communicating means includes at least one passage between said diaphragm and the adjacent wall of the tube body.

4. In a device of the character described producing ornamental bubble effects, a vertically disposed sealed transparent tube body, a translucent low-temperature boiling liquid column partially filling said tube body, a thin sheet material diaphragm positioned in the lower end of said tube body to provide a section space at the bottom end thereof, heated vapors of said liquid column expanded to occupy the section space with the liquid column retained above said diaphragm, said diaphragm having an opening therethrough

communicating said vapors with the liquid column to permit "flash" expulsion of expanding portions of said vapors as bubbles up through said opening and into the liquid column, said tube body formed with a heat dissipating upper end above the level of said liquid column to which the bubbles rising in the column pass for liquefaction, and heating means of sufficient supply directed to the "flash" expulsion vapors in the said section space for producing the ornamental bubble effects.

5. A device as defined in claim 4 in which said diaphragm opening is centrally located.

6. A device as defined in claim 4 in which said tube body lower end is provided with porous particles under said diaphragm.

7. A device as defined in claim 4 in which said diaphragm opening comprises a passage between said diaphragm and the adjacent wall of the tube body.

8. In a device of the character described producing ornamental bubble effects, a vertically disposed sealed tube body having a lower end, a column of low-temperature boiling liquid column partially filling said tube body, a thin sheet material diaphragm independently formed of said tube body positioned in said lower tube end in close proximity to the bottom thereof to provide a section space under said diaphragm and having at least one opening therein for communication between opposite sides thereof, and means carried by said diaphragm for retaining the latter in said position against movement.

9. The device as defined in claim 8 in which porous particles occupy said space.

10. A device for producing ornamental bubble effects comprising a vertically disposed sealed transparent tubular body, a column of volatile liquid under reduced atmospheric pressure contained therein, a relatively thin wall partitioning means to form a vapor pocket of predetermined capacity, said means including an annular portion immovably engaging a lower portion of said tubular body, and communicating means extending through said partitioning means to release and expand for "flash" expulsion portions of said vapor as bubbles from said pocket into the liquid column.

11. The device as defined in claim 4 in which said thin sheet material diaphragm is characterized by an annular flange immovably engaging said tube body.
